OTHER PUBLICATIONS Vasquez Collars & KP Equipment website, www.vasquezcollarsusa.com, Dec. 2009.*Primary Examiner* — Susan Moon Lee(74) *Attorney, Agent, or Firm* — QuickPatents, Inc.; Kevin Prince**(57) CLAIM**

What is claimed is the ornamental design for a chain collar for training dogs, as shown and described.

DESCRIPTION

FIG. 1 is a perspective view of a chain collar for training dogs, showing the new design;

FIG. 2 is a front elevational view thereof;

FIG. 3 is a rear elevational view thereof;

FIG. 4 is a left-side elevational view thereof;

FIG. 5 is a right-side elevational view thereof;

FIG. 6 is a top plan view thereof; and,

FIG. 7 is a bottom plan view thereof.
